Des. 205,178
Patented July 5, 1966

205,178

FRUIT JUICER

John H. Batchelor, Condado, Puerto Rico, assignor to Roto Rico, Inc., Carolina, Puerto Rico, a corporation of California

Filed Oct. 8, 1965, Ser. No. 87,374

Term of patent 14 years

(Cl. D2—3)

FIG. 1.

FIG. 2.

FIG. 1 is a perspective view of a fruit juicer embodying my new design, being a view taken from the front and top and one side thereof.

FIG. 2 is a perspective view of the instant design being a view taken from the back and bottom and other side thereof.

The dominant features of the design reside in the portions shown in full lines.

I claim:

The ornamental design for a fruit juicer, as shown and described.
